UNITED STATES PATENT OFFICE.

GEORGE R. POHL, OF WASHINGTON, DISTRICT OF COLUMBIA, ASSIGNOR TO
ROBERT LEDING, OF SAME PLACE.

DESIGN FOR A PLATE OR PLAQUE.

SPECIFICATION forming part of Design No. 33,628, dated December 4, 1900.

Application filed October 29, 1900. Serial No. 34,854. Term of patent 7 years.

To all whom it may concern:

Be it known that I, GEORGE R. POHL, a citizen of the United States, residing at Washington, District of Columbia, have invented 5 and produced a certain new and useful Design for Plates or Plaques; and I do hereby declare the following to be a full, clear, and exact description of the invention, such as will enable others skilled in the art to which it appertains to make and use the same.

The invention or production is illustrated in the accompanying drawing, showing a plate or plaque having the design applied thereto.

The main characteristic of the invention is 15 that the center of the design is occupied by a representation of the Washington monument *a*, having garlands of leaves *b b* entwined around it. Above the monument is a representation of the American eagle, as at *c*, and 20 surmounting the eagle is a scroll *d*. Beneath the monument there is a space *e* of generally oval form, and underneath this space is a central floral arrangement *f*, having branching therefrom and following the curved outlines 25 of the plate or plaque to which the design is applied sprays of leaves, the inner ends of these sprays being connected with the central floral arrangement *f* by ribbons *h h*. Crossing the center of the plate at right angles to 30 the representation of the monument *a* and extending from one edge of the plate to the other is a rectangular space *i*, inclosed by an ornamental border *i'*, the outline of which is broken at appropriate points *i'' i''* by recesses, 35 as illustrated in the drawing. On either side

of the representation of the monument *a* above and below its median line and occupying each a segment of the plate or plaque are spaces *k k' k'*, each of these spaces being surrounded by an ornamental scroll-like border 40 *l l' l'*, and the portions around the periphery of the plate between the spaces above described are filled in with an ornamental floral and scroll-like decoration *m m* and *n n*.

The general configuration of the spaces *k' k'* 45 and *e* in the lower part of the design is that of an oval, and to further embellish this portion of the design a star *s* is appropriately located at the top of the space *e* just under the representation of the monument.

The outline of the spaces *k k* in the upper portion of the drawing is similar to that of the lower spaces, except that their outer upper edges are arched, as shown at *t t*. The upper end of the monument extends between these 55 spaces *k k*, and the ornamental scrollwork forming the outline of the spaces is worked into a fluted design *s'*, encircling the capstone of the monument.

Having thus described the invention, what 60 I claim, and desire to secure by Letters Patent, is—

The design for a plate or plaque substantially as herein shown and described.

In testimony whereof I affix my signature 65 in presence of two witnesses.

GEORGE R. POHL.
